UNITED STATES PATENT OFFICE.

HENRY B. DOMINICK, OF NEW YORK, N. Y.

DESIGN FOR FORK AND SPOON HANDLE.

SPECIFICATION forming part of Design No. 12,250, dated May 10, 1881.

Application filed March 17, 1881. Term of patent 7 years.

To all whom it may concern:

Be it known that I, HENRY B. DOMINICK, of the city, county, and State of New York, have invented a new and Improved Design for Fork and Spoon Handles, of which the following is a full, clear, and exact description.

Figure 1 is an elevation and cross-section of my newly-designed fork and spoon handle of triangular cross-section. Fig. 2 is an elevation and cross-section of my newly-designed fork and spoon handle of pentagonal cross-section. Fig. 3 is an elevation and cross-section of my newly-designed fork and spoon handle of parallelogramic cross-section. Fig. 4 is an elevation and cross-section of my newly-designed fork and spoon handle of hexagonal cross-section. Fig. 5 is an elevation and cross-section of my newly-designed fork and spoon handle of octagonal cross-section. Fig. 6 is an elevation and cross-section of my newly-designed fork and spoon handle of square cross-section.

The handles herein shown have respectively three, four, five, six, and eight flat sides, and taper from their apices to their bolsters,

and from thence their lower portions are spirally grooved or twisted. Any other number of flat sides may be given to the handles without departing from my design.

The leading feature of my design for a handle consists in a tapering flat-sided upper portion of polygonal cross-section and with pyramidal apex, and in a spirally grooved or twisted lower portion.

A represents the tapering flat-sided upper portion, of polygonal cross-section, with pyramidal apex B, and C the spirally grooved or twisted lower portion, of the handle.

Having thus described my invention, I claim as new and desire to secure by Design Patent—

The design for a fork or spoon handle, herein shown and described, the same consisting of a tapering flat-sided upper portion of polygonal cross-section and pyramidal apex, and a spirally grooved or twisted lower portion.

HENRY BLANCHARD DOMINICK.
